R. B. HICKS.

PUMP CONTROL.

APPLICATION FILED MAY 1, 1917.

Patented Jan. 15, 1918.

UNITED STATES PATENT OFFICE.

ROBERT BRUCE HICKS, OF NEW YORK, N. Y., ASSIGNEE TO WILLIAM E. QUIMBY, INC.,
OF NEW YORK, N. Y., A CORPORATION OF NEW YORK.

PUMP CONTROL.

1,253,687.

Specification of Letters Patent. Patented Jan. 15, 1918.

Application filed May 1, 1917. Serial No. 165,718.

To all whom it may concern:

Be it known that I, ROBERT BRUCE HICKS, a citizen of the United States, residing at New York city, in the county and State of

5 New York, have invented new and useful Improvements in Pump Controls, of which the following is a specification.

My invention relates to a pump control and hot water return mechanism whereby 10 the hot water of condensation from radiators, etc., is collected and fed to the boiler by an automatically controlled pump. The essential features of my invention are a reservoir or tank for the condensation water, 15 a pump to deliver the water therefrom to the boiler, a motor for the pump, a pressure actuated controlling means arranged outside of the reservoir and adapted to be moved into operative position by the rise of the 20 water in the tank, a switch operated by the controlling means, a connection from the switch to the pump, and a by-pass pipe from the pump to the controlling means whereby the latter is maintained in starting position 25 by the pressure from the pump until the water in the tank is exhausted and the suction uncovered. It is arranged that when the tank is filled the pressure of the water will actuate the controlling means initially 30 to close the control circuit for operating the pump and that thereafter the circuit will be maintained and closed by the pressure from the pump.

My invention will be understood by reference to the accompanying drawing wherein a desirable embodiment thereof is illustrated, and wherein the reference numerals of this description are applied to the corresponding parts in the several views. There- 35 in Figure 1 is a view in elevation showing an approved arrangement of my invention. Fig. 2 is a sectional view showing a controlling device in detail and Fig. 3 is a view similar to Fig. 1 illustrating a slightly modified arrangement.

In the arrangement disclosed 1 indicates a suitable base for the entire installation, 2 is the tank having the intake 3 for the condensation water and the vent 4. At 6 is 40 shown the pump having volute 7 and pipe 8 from the tank, and a motor 10 is connected to the pump by the shaft 11 provided with the usual coupling 12.

The main circuit 13 from the line wires 55 to the pump is closed by a suitable switch

14 mounted upon switch support 16 and operated by a magnet 15 energized by a controlling circuit 17 which is opened and closed by a controller switch arm 18 co-acting with upper and lower contacts 19, 19'. 60 The switch arm 18 of the controlling device is arranged to be actuated by the pressure of the fluid, and to this end is arranged, as shown, to be actuated by a suitable dia- 65 phragm 20 positioned within a chamber in the controller casing 21. The switch arm is fulcrumed at 22 and is engaged by a post 23 carried by the diaphragm as indicated. At 24 is a connection from the tank communicating with the chamber beneath the dia- 70 phragm and 25 indicates a similar connection or by pass from the pump discharge pipe 28 to said chamber, this by-pass preferably being provided with a regulating valve 26 as indicated. As will be readily 75 understood from the arrangement described, pressure exerted by the fluid beneath the diaphragm will operate to lift the switch arm 18, from its normal lower position shown, into engagement with the upper contact 19 to close the controlling circuit 17.

At 29 there is shown an auxiliary switch for manually closing the controlling circuit 17 to operate the main switch 14 when the switch arm 18 is in normal lowered position, 80 as shown, at which time it rests upon the lower contact 19'. This permits of operating the pump to empty the tank independ- 85 ently of the automatically operating controlling devices; it being understood that 90 the valve 26 is first closed before the circuit 17 is thus manually closed by the switch 29.

In the modified form of Fig. 3 the by 95 pass pipe 25 is connected with the pump volute, adjacent the top thereof. This ar- arrangement is particularly desirable for the reason that the pipe 24 provides a passage for the escape of air or steam, preventing its accumulation in the top of the pump volute. This latter condition, or steam binding, 100 often occurs in the use of pumps in the ar- rangement here described and greatly im- pairs the proper operation of the pump.

From the foregoing it will be understood that when the tank is filled to the outlet 24, 105 and a few inches above, pressure of the water will be exerted on the diaphragm to shift the switch arm 18 responsive to the water pressure and thereby the switch 14 will be closed, closing the main circuit, the 110

current will pass and the motor will start the pump, and as the water falls in the tank the diaphragm will be held up in operative position by the pressure through the by-pass pipe so long as the pump is operating and any water is being pumped, thus insuring the emptying of the tank once the pump is started. So long as the pump is operating and pumping water, there will be an excess pressure in the pump volute, which is exerted through the by-pass pipe to maintain the diaphragm in operative position it being understood that the by-pass pipe is larger than the opening from the diaphragm chamber to the tank. When empty there is no more water passing, consequently no pressure to hold the diaphragm up, and the contacts are then separated, the switch is opened and the pump is then cut out until the tank is again filled.

I believe that this manner of applying power from the pump volute to any regulating or control mechanism is broadly new and therefore I desire to claim the same broadly.

Furthermore my particular arrangement and combination of parts is desirable and an improvement over any form of control for a similar purpose, with which I am acquainted. I am aware that pumps and motors for similar purposes have been controlled by a float arranged within the tank but such arrangement had many disadvantages—there was constant danger of rusting and of injury to the parts; a man hole was necessary for access to the parts to make repairs; in that case the whole apparatus had to be shut down; also holes had to be tapped for the switch; the entire tank would not be emptied; the float requires a large tank, and cannot prolong the operation, for it operates through a small range only.

By my present arrangement of an exterior diaphragm control, or other desirable exterior regulator, all those disadvantages are overcome, there is little danger of the diaphragm getting out of order, and, if it does, it can be quickly and easily repaired or a new diaphragm substituted almost in an instant and at a trifling cost.

Having described my invention I claim,

1. The combination of a tank, a pump associated therewith, means for controlling the operation of the pump arranged to be actuated by the contents of the tank and means actuated by the fluid pressure from the pump operative to maintain the pump in operation until cessation of the fluid pressure, substantially as described.

2. In a controlling device of the character described having in combination a tank, a pump associated therewith, means for controlling the operation of the pump arranged to be actuated by the contents of the tank

and a connection between the pump and the controlling device to transmit pressure from the pump thereto to maintain the pump in operation substantially as described.

3. The combination of a tank, a pump associated therewith, a controlling circuit for the pump, pressure actuated means for closing said circuit arranged to be actuated by the contents of the tank and a connection from the pump to the pressure actuated means to exert pressure on said means to maintain the pump in operation substantially as described.

4. The combination of a tank, a pump connected therewith, a motor operatively connected to the pump, a controlling circuit therefor, a switch for closing said circuit, a diaphragm connected to operate the switch, and arranged within a chamber communicating with the tank, and a connection from the pump to the diaphragm chamber whereby the diaphragm will be operated to close the switch by pressure from the tank and maintained closed by pressure from the pump substantially as described.

5. The combination of a tank, a pump connected therewith, a motor operatively connected to the pump, a controlling circuit for the motor, a switch for closing said circuit, a diaphragm chamber communicating with the tank and with the pump, a diaphragm within the chamber connected to operate the switch and adapted automatically to be operated by pressure from the tank to close the motor controlling circuit and by pressure from the pump to maintain the circuit closed and means for independently closing of the motor circuit, substantially as described.

6. The combination of a tank, a pump connected therewith, a motor connected to operate the pump, a controlling circuit therefor, a switch for closing said circuit, a diaphragm chamber communicating with the interior of the tank, a diaphragm within said chamber connected to close the switch under pressure from the tank, a connection from the diaphragm chamber to the pump whereby the diaphragm will maintain the switch closed under pressure from the pump, a valve in said connection and a switch for independently closing the pump circuit, substantially as described.

7. In a controlling device of the character described having in combination, a tank, a rotary pump associated therewith, means for controlling the operation of the pump arranged to be actuated by the contents of the tank and a connection providing a passage from the pump to the controlling means to transmit pressure from the pump thereto operative to maintain the pump in operation, and said connection being made to the top portion of the pump volute, substantially as described.

8. The combination of a tank, a pump connected therewith, a motor operatively connected to the pump, a controlling circuit therefor, a switch for closing said circuit, a diaphragm connected to operate the switch and arranged within a chamber having an opening communicating with the tank, a by pass connection from the pump to the diaphragm chamber providing a passage larger

than the opening from the chamber to the tank whereby the diaphragm will be operated to close the switch by pressure from the tank and maintained closed by pressure from the pump.

In testimony whereof I have signed my name to this specification.

ROBERT BRUCE HICKS.
